[57] CLAIM

The ornamental design for a tire, as shown and described.

DESCRIPTION

FIG. 1 is a perspective view of a tire according to the present invention, wherein the tread pattern repeats uniformly throughout the circumference of the tire;

FIG. 2 is a front view of the tire of FIG. 1, it being understood that the back view is a mirror image thereof; and,
FIG. 3 is a side view of the tire of FIG. 1, it being understood that the other side is a mirror image thereof.
